UNITED STATES PATENT OFFICE.

WILLIAM C. TREGONING, OF CLEVELAND, OHIO, ASSIGNOR TO THE TREGONING ELECTRIC MANUFACTURING COMPANY, OF CLEVELAND, OHIO, A CORPORATION OF OHIO.

ATTACHMENT-PLUG.

No. 861,238.

Specification of Letters Patent.

Patented July 23, 1907.

Application filed January 9, 1907. Serial No. 351,504.

To all whom it may concern:

Be it known that I, WILLIAM C. TREGONING, a citizen of the United States of America, and a resident of Cleveland, in the county of Cuyahoga and State of Ohio, have invented certain new and useful Improvements in Attachment-Plugs, of which the following is a specification.

My invention relates to improvements in attachment plugs, and has for its object the provision of an appliance of this character, wherein the insulating properties and the contacts are maintained at the highest efficiency; the device is made of simple and compact form, and admits of readily making and breaking the electrical connections as required.

15 In apparatus of this character, it is necessary that the contacts shall make perfect electrical engagement, and that those parts which are energized or excited by the transmitted current, shall be securely mounted and completely insulated from each other. Moreover, 20 it is of importance that the contacts, while securing the above results, shall not be shaped in such manner as to unduly lock or grip each other, but preferably by their positioning and proper form; these contacts should immediately be engaged or released. My improvements are adapted to attain these results, and as 25 embodied herein, are shown in connection with a removable-cap attachment-plug, equipped with various modified means for maintaining the desired electrical connection. These means are associated preferably 30 with porcelain body portions, serving to maintain and insulate the springs and conductor members, and secured together respectively by means of connecting contact springs, and by a central stem electrically and mechanically uniting the removable-cap. All of these 35 features will be more readily understood by making reference to the accompanying sheet of drawings, illustrating in detail the features of my invention wherein:

Figure 1, is a vertical section of the improved attachment plug embodying my invention. Fig. 2, is an end view of the removable cord-socket member. Fig. 3, shows the inner end of the attachment plug with the porcelain body of the cap removed. Fig. 4, is a plan view of the opposite end thereof. Figs. 5 and 11, are fragmentary views showing modified forms of co-acting 45 separable springs. Fig. 6, illustrates the conductive shell of the removable-cap. Fig. 7, is a perspective view of the porcelain body of said cap; and Figs. 8, 9 and 10 respectively show in perspective, one of the contact springs, a tapped part, and the bur for securing 50 the removable-cap of the plug.

In each of the several figures of the drawing, I have indicated similar parts by the same character of reference, to avoid any confusion in considering the same.

Referring first to Fig. 1, it is seen that the attachment 55 plug is therein shown by the sectional view in inverted

position with the separable cord-socket above, and the connecting cap beneath. Each of the three sections of the plug is provided with a specially shaped body-member *a*, *b* or *c* of suitable insulating material, such as porcelain. Body portion *b* is provided with two longitudinal channels or passages *b'*, respectively accommodating the contact springs *d* *d'* having corrugated ends. One of said springs is shown in detail in Fig. 8. At the inner end of body portion *b* is provided an upwardly extending U-shaped wall *b''*, within and around which the contact parts respectively lie in compact relation, but thoroughly insulated from each other, as best shown in Fig. 3. Extending centrally through this plug or body portion, is the screw *e*, which serves to assemble the several parts, and terminates slightly beyond the body portion *a* of the cap, which is recessed to receive the bur *e'*, while the tapped part *e''* (Fig. 9) intermediately engages the screw to hold the contact spring *d'* in place. The shell *f* of the removable-cap is thus maintained in engagement with contact spring *d*, 70 while the opposing spring maintains contact through the screw *e* and its terminal bur. As shown in Figs. 6 and 7, the shell and the insulating body portion are suitably recessed or cut away to accommodate the insulating wall *b''*. From the central bore or opening *c''* of 75 the separable cord-socket *c*, will extend the connecting cord (not shown) to any desired appliance, while the corrugated springs *g* *g'* are respectively mounted therein, and diametrically positioned to extend within the longitudinal openings *b'*, and separately engage with 80 the co-acting springs *d* *d'*. It will be seen that this type of attachment-plug affords contact springs of unusual length, and the corrugated portions thereof are adapted to engage and make highly effective contact with each other. These corrugations preferably 85 are not abrupt and thereby unduly resisting separation, but by reason of the relatively long frictional contact surfaces afforded between the springs, they are admirably adapted to serve both as attachment and contact springs. Moreover, the length of spring serves to distribute the flexure, so that there is no chance of breakage at the point of attachment, while the frictional engagement is better regulated or adjusted. The springs for both separable-members, furthermore, are adapted to be stamped out of sheet-metal, thus materially reducing the cost, and they are provided with integral angular extensions, affording ample means for mechanical and electrical attachment thereof, without resort to soldering or riveting the same to the adjacent parts.

In the fragmentary view, Fig. 5, I have shown contact-springs *d''* and *g''*, the former having a reversely bent loop or crook, which is adapted to engage with the lower end of the separable spring *g''*. The modified types of springs *d* *g'*, shown in Fig. 11, are provided 105

with single corrugations at their ends, and while the engaging contact surfaces are not so large as in the other types just described, an attachment-plug thus equipped, is capable of immediate separation resulting from a strain or pull imparted thereto at any angle. By reason of the relatively wide springs, however, the electrical and mechanical engagement may be made sufficient through the use of springs of proper stiffness and rigidity, as shown, to meet all practical requirements in a device of this character, while the integral bent attaching terminals for the springs, afford ample flexure without the chance of breaking off the spring, as with a short or soldered connection, for example. This is frequently found to be a very desirable feature, since the connecting cord may otherwise accidentally over-turn the terminal lamp, fan-motor, or other appliance, should the attachment-plug not separate immediately the conducting cord is drawn taut from any cause.

20 It will be appreciated that the several connections within my attachment-plug will be soldered, as in ordinary practice, and that the screw openings 'c' in the removable cord-socket member will be filled with wax, or other insulating material, after the cord strands have been properly connected thereto. Moreover, certain modifications from the precise details herein set forth, will occur to those skilled in the art, and fall within the spirit of my invention.

Having now set forth the preferred embodiment of 30 said invention, I claim as new, and desire to secure by Letters Patent the following:

1. In an attachment-plug, the combination with a contact-making cap formed of an insulating body portion, an exterior metal sleeve therefor, and an integral contact and retaining spring secured to said body portion with its bent terminal interiorly contacting with the sleeve and held in place thereby, of an insulating body portion having two longitudinal passages extending therethrough, a contact and retaining spring mounted thereon, and lying within one of said passages, while the opposing contact and retaining spring extends within the other of said passages, and a separable member of insulating material mounting two co-acting contact and retaining members adapted to enter said passage and respectively engage the aforesaid springs; the said springs being provided with interlocking engaging parts to secure the mechanical and electrical attachment of the separable part, substantially as set forth.

2. In an attachment-plug, the combination with an insulating body portion, of a contact-making cap or shell surrounding the same, a contact and retaining spring having an integral attachment terminal secured beneath said shell, an insulating body portion associated therewith and provided with two longitudinal passages, within one of 55 which the spring extends, a second contact and retaining spring secured upon said body portion and lying within the other passage, a central attaching screw, and a separable member of insulating material with two co-acting contact and retaining parts mounted thereon in position to engage the aforesaid springs, whereby the separable member is electrically and mechanically attached to the body of the plug, substantially as set forth.

3. In an attachment plug, the combination with a contact-making cap, of an insulating body portion having two

longitudinal passages extending therethrough, two combined retaining and contact springs respectively disposed in said passages, each having integral angular extensions securely mounting its upper end and connected with the terminals of the contact-making cap, and a separable member of insulating material mounting two contact springs, adapted to enter said passages and respectively engage the aforesaid springs; the said springs being corrugated adjacent to their engaging portions, substantially as set forth.

4. In an attachment plug, the combination with a contact-making cap, of an insulating body portion having an elevated U-shaped insulating wall separating the respective conductor parts, and two longitudinal passages extending therethrough, combined retaining and contact springs respectively disposed in said passages and connected with the terminals of the contact-making cap, and a separable member of insulating material mounting two contact springs, adapted to enter said passages and respectively engage the adjacent springs; the said springs being corrugated adjacent to their engaging end portions, substantially as set forth.

5. In an attachment plug, the combination with the insulating members 'a', 'b', and 'c', respectively forming the cap, body and cord-socket bases, of two combined retaining and contact springs extending through and mounted upon said body member 'b', a conductive shell about the member 'a' interiorly engaging the terminal of one of said springs, a central screw uniting these parts, and contact springs upon the member 'c', adapted separably to engage the adjacent contact springs; said springs being corrugated adjacent to their engaging end portions, substantially as set forth.

6. In an attachment plug, the combination with an elongated insulating body portion, traversed by two longitudinal passages, of two relatively long combined retaining and contact springs substantially equal in length to the elongated body portion and respectively lying therein; each having integral angular extensions securely mounting its upper end, circuit-extending contacts respectively connected therewith, and a cord-socket member adapted to be removably associated with said body portion and having two co-acting attaching and contact springs; the adjacent springs being corrugated over substantially their entire engaging areas, substantially as set forth.

7. In a separable attachment plug, the combination with a contact-making cap, or an insulating body portion, having an elevated U-shaped insulating wall separating the respective conductor-members, two combined retaining and contact springs mounted within said body; each having integral angular extensions securely supporting its upper end, and a separable member, comprising an insulating base and two coacting contact springs respectively adapted to engage the adjacent springs; all being corrugated throughout substantially their engaging areas, substantially as set forth.

8. In a separable attachment plug, the combination with a suitable contact-making cap, of an insulating body portion having an integral U-shaped wall, a contact spring having a bifurcated supporting terminal, a second contact spring 'd' and integral terminal, a tapped part 'e'' engaging and supporting said terminal, a central assembling and contact-making screw 'e' and a separable member mounting two coacting contact springs; all of said springs being corrugated throughout approximately their engaging areas, substantially as set forth.

Signed at Cleveland, this 8th day of January, 1907, in the presence of the two subscribing witnesses.
